PRESSURE FLUID MOTOR

Original Filed June 14, 1935

UNITED STATES PATENT OFFICE

2,195,204

PRESSURE FLUID MOTOR

Elmer G. Gartin, Claremont, N. H., assignor to
 Sullivan Machinery Company, a corporation of
 Massachusetts

Application June 14, 1935, Serial No. 26,653
 Renewed June 5, 1939

8 Claims. (Cl. 121—12)

My invention relates to pressure fluid motors, and more particularly to improved blow varying means for a percussive motor of the type normally used for rock drilling and similar purposes.

An object of my invention is to provide an improved pressure fluid hammer motor having incorporated therein improved blow varying means. Another object is to provide an improved pressure fluid motor of the impact type especially designed for use with rock drills or other impact tools and having improved means incorporated therein for varying the blow struck so that heavy, medium or light blows may be transmitted to the working implement as desired.

Still another object of the invention is to provide an improved pressure fluid motor of the type mentioned having improved blow varying means permitting extremely simple changing from one blow-force to another, and in which improved means is provided for precluding any irregularity in the operation of the motor during drilling in ground where rearward movements of the piston are retarded due to resistance to rotation. These and other objects of the invention will hereinafter more fully appear.

In the accompanying drawing in which there is shown for purposes of illustration one form which the invention may assume in practice,

Fig. 1 is a view in longitudinal section through a percussive motor having embodied therein the illustrative embodiment of the improved blow varying means.

Fig. 2 is a transverse section on a plane corresponding to the line 2—2 of Fig. 1.

Fig. 3 is a horizontal section on a plane corresponding to the line 3—3 of Fig. 1.

Fig. 4 is a fragmentary sectional view on the plane of the section line 4—4 of Fig. 2.

Fig. 5 is a view similar to that of Fig. 4 and taken on the plane corresponding to the line 5—5 of Fig. 2.

Fig. 6 is a transverse section on a plane corresponding to the line 6—6 of Fig. 1.

Fig. 7 is a sectional view through the drill cylinder on a plane corresponding to the line 7—7 of Fig. 2.

Fig. 8 is a view partially in elevation and partially in transverse section on the plane corresponding to the line 8—8 of Fig. 1 with the 50 parts in a different position.

Fig. 9 is a section on the plane corresponding to the line 9—9 of Fig. 8.

Referring to the drawing, it will be observed that a pressure fluid operated percussive motor 55 is shown and has a cylinder 2 having a bore

3 in which a hammer piston 4 is reciprocable. The hammer piston 4 has a striking bar 5 having grooves 6 therein which cooperate with a chuck nut 7 to effect rotation, through any suitable mechanism, of a percussive tool 8 which is adapted to be struck by the striking bar 5 on the forward movements of the hammer piston 4. Intermittent rotation of the hammer piston is effected by means of a rifle bar 10, herein formed integral with its pawl carrier 11 supporting pawls 12 cooperating with the ratchet ring 13 mounted in a rear head member 14 which cooperates with the cylinder 2 in maintaining in position a rear cylinder head 15. A valve mechanism generally designated 16 comprises a valve chest 17 having a bore 18 in which a multi-spool valve 19 is reciprocably mounted. Under the control of a manually movable throttle valve 20, pressure fluid is admitted from any suitable supply connection 21 through a passage 22 to a central supply groove 23 in the valve chest; and a groove 24 in the valve 19 is adapted to connect the supply groove 23 with the passage 25 opening into the rear end of the cylinder bore 3 to effect forward motion of the piston. Another groove 26 in the valve 19 is adapted to connect the supply groove 23, in a different position of the valve, with a passage 27 leading to the forward end of the cylinder bore 3. Exhaust grooves 28, 29 are formed in the valve chest and are alternatively connectible respectively with the connections 25 and 27 to effect exhaust from the rear and forward ends of the cylinder. The valve 19 is thrown in opposite directions by appropriate means, the means for throwing the valve to the position for effecting admission to the rearward end of the cylinder including a port 32 opening into the bore of the cylinder at a position in which it will be uncovered after the piston 4 has traveled a predetermined desired amount in a rearward direction, the port 32 being connected by a passage 33 with the space 34 at the rearward end of the valve chest.

As the force of the blow struck will vary with the time when the valve 19 is thrown into its position for interrupting fluid supply to the rear end of the piston, it will be seen that by appropriately varying the instant of admission of throwing fluid to the forward end of the valve, different periods of admission to the rear end of the cylinder and different forces of blow can be accomplished. For the purpose of providing for this result, I have shown herein three throwing passages extending through the wall of the 55

cylinder radially at a point just forward of the forward end of the valve chest. The three passages mentioned are respectively designated 36, 37 and 38, and the outer ends of these passages open into a bore 39 in which there is rotatably mounted an annular valve 40 whose structure will be shortly described. The passage 37 is provided with an enlargement 42 at its inner end, and the rearward end of this enlargement is uncovered by the piston 4 on the forward stroke of the latter somewhat before the mouth 32 of the port 33 is covered. The passage 38 has at its inner end a still longer enlargement 43, and its rearward end is uncovered by the piston 4 on the forward strokes of the latter at a still earlier time. The valve 40 is provided with a peripheral notch 45 which opens at the periphery of the valve into communication with the outer ends of the passages 36, 37 and 38, selectively, while the notch also opens through the end face 46 of the valve, and therefore is communicable selectively with the outer ends of passages 47, 48 and 49 extending through the end of a valve chest bushing 58 and lying in the same radial planes respectively with the ports 36, 37 and 38 in the cylinder wall. The valve member 40 is also provided with a pair of passages extending obliquely therein and numbered 51 and 52 respectively, these passages being spaced apart by a greater angle than the angular distance between the passages 48 and 49, the angle between them being so selected that when the notch 45 is in communication with the port 37 the passage 51 will be in communication with the port 49. Correspondingly, when the notch 45 is in communication with the port 38 the passage 52 will be in communication with the port 48. The passages 51 and 52 at their forward ends open into an annular internal recess 53 in the valve member 40. The valve member 40 is slidably supported on a boss 54 formed integral with the liner member 50 and houses a spring 55 which abuts a shoulder 56 at the rearward end of the annular recess 53 and at its forward end abuts a transverse pin 57 secured in the projecting boss; and said spring normally presses the valve member 40 into its rearward position. For the purpose of holding the valve member 40 in the desired different angular relations, it is provided with a pin 58 which is adapted to operate with different ones of three notches 59, 60 and 61 suitably formed in the forward face of the valve chest member so that the notch 45 may come opposite the desired one of the several passages 37, 36 and 38.

The mode of operation of the device will be readily understood from what has been said. With the valve 40 in the position shown in Figs. 1 and 2 and held in that position by engagement of the pin 58 with the notch 60, it will be readily understood that the motor will operate in an entirely normal manner, the valve being thrown in a rearward direction to interrupt admission to the rearward end of the cylinder and initiate admission to the forward end of the motor cylinder when the rearward end of the piston uncovers the inner end of the port 36. With the valve 40 in the position just described, the end of the valve member 40 will blank off the ports 48 and 49. When a lighter blow is desired, the valve member 40 will be retracted against the force of the spring to withdraw the pin 58 from the notch 60 and cause its engagement in the notch 59, as in Fig. 8. This will bring the notch 45 in the valve 40 opposite the port 37 and will con-

nect, through the notch 45, the port 37 with the passage 48. The passage 51 will then connect the passage 49 with the atmosphere (see Fig. 9). It will be observed that the piston 4 on its forward travel will now uncover the rearward end of the enlargement 42 at the inner end of the throwing passage 37 earlier in the forward stroke of the piston, and accordingly will shift the valve 19 to effect cut-off for the rear end of the cylinder and admission to the forward end of the cylinder earlier in the stroke. The size of the passage 51 will be made such as to prevent its having any material effect on the rearward throwing of the valve 19. Its utility will be appreciated when it is understood that upon the rearward strokes of the piston 4 such as might occur in drilling in very sticky ground, a retardation of the piston 4 might give time, after the passage 32 is uncovered by the forward end of the piston and before the rearward end of the enlarged mouth 42 of the passage 37 is covered, for forward throw of the valve 19 and some admission through the passage 25 to the rear end of the cylinder and back through the passage 42 to the front face of the valve, and cause interference with smooth working of the motor.

When a still shorter stroke is desired, the valve 40 will be pulled outwardly against the pressure of the spring 55 and rotated to bring the notch 45 opposite the passage 38. This will cause the earliest admission to the front end of the valve chest, and accordingly the lightest blow. The danger of fluttering of the valve and irregularity of motor operation will also be precluded in this case because the passage 52 will then come opposite the port 48 and bleed away any pressure which might enter the extreme end of the passage 43, and so prevent its tending to throw the valve in the opposite direction.

From the foregoing description it will be observed that I have provided an extremely simple and convenient arrangement for effecting a variation in the force of blow struck. It will be noted that the parts are in convenient position, occupy extremely little space, are readily adjustable, and not only provide for the necessary pre-throwing, as it were, of the valve to effect a reduction in the force of blow, but also guard against any fluttering of the valve and any irregularity of operation due to the provision of the facilities for valve throwing.

While I have in this application specifically described one form which my invention may assume in practice, it will be understood that this form of the same is shown for purposes of illustration, and that the invention may be modified and embodied in various other forms without departing from its spirit or the scope of the appended claims.

What I claim as new and desire to secure by Letters Patent is:

1. In a pressure fluid hammer motor, a cylinder having a bore, a hammer piston reciprocable therein, a fluid actuated distributing valve, and throwing means for said valve including a pressure area on said valve effective on fluid admission thereto to shift said valve to a position for effecting interruption of admission to the rear end of the cylinder and admission to the forward end of the latter and means for conducting pressure fluid from the cylinder bore to said pressure area on said valve at different times during the forward travel of the piston, said means including a plurality of passages having communication with the cylinder bore and re-

spectively initially uncovered by the piston at different times in the forward travel of the piston, and adjustable means including a rotary valve member arranged coaxially with the fluid distributing valve for selectively rendering said passages effective upon movement of said rotary valve into different positions, and means for providing a restricted vent for said area made effective by said rotary valve when the latter is in at least one of its positions for effecting earlier distributing valve throw.

2. In a pressure fluid hammer motor, a cylinder having a bore, a hammer piston reciprocable in said bore, a fluid actuated distributing valve, and throwing means therefor including a pressure area on said valve effective on fluid admission thereto to shift said valve to a position for effecting interruption of admission to the rear end of the cylinder and admission to the forward end of the latter and means for conducting pressure fluid from said cylinder bore to said pressure area on said valve at different times during the forward travel of the piston, said means including a plurality of passages having communication with the cylinder bore and respectively initially uncovered by said piston at different times in the forward travel of the piston and adjustable means including a rotary valve member arranged coaxially with said fluid distributing valve for selectively rendering said passages effective upon movement of said rotary valve into different positions, and means for providing a restricted vent for said area made effective when said rotary valve member is in any of its positions for effecting earlier distributing valve throw.

3. In a pressure fluid hammer motor, a cylinder having a bore, a hammer piston reciprocable therein, a fluid actuated distributing valve, and throwing means for said valve including a pressure area on said valve effective on fluid admission thereto to shift said valve to a position for effecting interruption of admission to the rear end of the cylinder and admission to the forward end of the latter and means for conducting pressure fluid from said cylinder bore to said pressure area on said valve at different times during the forward travel of the piston, said means including a plurality of passages having communication with the cylinder bore and respectively initially uncovered by said piston at different times in the forward travel of the piston and means for selectively rendering said passages effective, and means for restrictively venting said pressure area when early valve throwing is to be effected.

4. In a pressure fluid hammer motor, a cylinder having a bore, a hammer piston reciprocable in said bore, a fluid actuated distributing valve, and throwing means for said valve including a pressure area on said valve effective on fluid admission thereto to shift said valve to a position for effecting interruption of admission to the rear end of the cylinder and admission to the forward end of the latter and means for conducting pressure fluid from said cylinder bore directly to said pressure area on said valve at different times during the forward travel of the piston, said means including a plurality of passages having communication with the cylinder bore and respectively initially uncovered by said piston at different times in the forward travel of the latter and means for controlling said pressure fluid conducting means including a rotary valve member arranged coaxially with said dis-

tributing valve and having passages means communicable selectively with the passages communicating with the cylinder bore upon movement of the rotary valve into different positions, and means for providing a restricted vent for 5 said pressure area also including passage means on said rotary valve effective to vent said pressure area when said rotary valve is in at least one of its positions for effecting earlier throw of said distributing valve.

5. In a pressure fluid hammer motor, a cylinder having a bore, a hammer piston reciprocable in said bore, a fluid actuated distributing valve, and throwing means for said valve including a pressure area on said valve effective on fluid 15 admission thereto to shift said valve to a position for effecting interruption of admission to the rear end of the cylinder and admission to the forward end of the latter and means for conducting pressure fluid from said cylinder bore 20 directly to said pressure area on said valve at different times during the forward travel of the piston, said means including a plurality of passages having communication with the cylinder bore and respectively initially uncovered by said 25 piston at different times in the forward travel of the piston and means for controlling said pressure fluid conducting means including a rotary valve member arranged coaxially with said distributing valve and having passage means communicable selectively with the passages communicating with said cylinder bore upon movement of said rotary valve into different positions, and means for providing a restricted vent for said 30 pressure area including passage means on said 35 rotary valve for venting said pressure area when said rotary valve is in any of its positions for effecting earlier throw of said distributing valve.

6. In a pressure fluid hammer motor, a cylinder having a bore, a hammer piston reciprocable 40 in said bore, a fluid actuated distributing valve, and throwing means for said valve including a pressure area on said valve effective on fluid admission thereto to shift said valve to a position for effecting interruption of admission to the rear 45 end of the cylinder and admission to the forward end of the latter and means for conducting pressure fluid from said cylinder bore directly to said pressure area at different times during the forward travel of the piston, said means including a plurality of passages having communication with the cylinder bore and respectively initially uncovered by said piston at different 50 times in the forward travel of the piston and means for controlling said pressure fluid conducting means including a passage with which said plurality of passages are selectively communicable, and means for restrictively venting said pressure area when early throwing of said 55 distributing valve is to be effected including a vent passage included in said controlling means.

7. In a pressure fluid hammer motor, a cylinder having a bore, a hammer piston reciprocable therein, a fluid actuated distributing valve, and throwing means for said valve including a pressure area on said valve effective on fluid admission thereto to shift said valve to a position for effecting interruption of admission to the rear end of the cylinder and admission to the forward end of the latter and means for conducting 65 pressure fluid to said pressure area at different times during the forward travel of the piston, said means including a plurality of passages having communication with the cylinder bore and respectively initially uncovered by said pis- 70

- ton at different times in the forward travel of the piston and means for controlling said pressure fluid conducting means and including a movable valve member arranged coaxially with said distributing valve for selectively rendering said plurality of passages effective, and means for providing a restricted vent for said area made effective by said movable valve member when the latter is in at least one position for effecting earlier distributing valve throw.
8. In a pressure fluid hammer motor, a cylinder having a bore, a hammer piston reciprocable in said bore, a fluid actuated distributing valve, and throwing means for said valve including a pressure area on said valve effective on fluid admission thereto to shift said valve to a position for effecting interruption of admission to the rear end of the cylinder and admission to the forward end of the latter and means for conducting pressure fluid from the cylinder bore

directly to said pressure area at different times during the forward travel of the piston, said pressure fluid conducting means including a plurality of passages having communication with the cylinder bore and respectively initially uncovered by said piston at different times in the forward travel of the piston and a movable valve member arranged coaxially with said distributing valve and having passage means formed therein and communicable selectively with said passages communicating with the cylinder bore upon movement of said movable valve member into different positions, and means for providing a restricted vent for said pressure area when said valve is in at least one of its positions for effecting earlier throw of said distributing valve, said last mentioned means including passage means formed in said movable valve member.

ELMER G. GARTIN. 20
